[57] CLAIM

The ornamental design for a paint brush wipe bar with dual
wiping surfaces, as shown.

DESCRIPTION

FIG. 1 is a top view for a paint brush wipe bar with dual
wiping surfaces showing my new design.

FIG. 2 is a bottom view.

FIG. 3 is an edge view of the serrated edge shown in FIGS.
1 and 2.

FIG. 4 is an edge view of the smooth edge shown in FIGS.
1 and 2; and,

FIG. 5 is an end view of the invention as shown in FIGS. 1,
2, 3, and 4, both ends being identical in all four FIGS.
